UNITED STATES PATENT OFFICE.

PREM NARAYAN, OF BIJNOR, INDIA.

MONOGRAMMIC ADVERTISING APPARATUS.

Application filed October 5, 1925, Serial No. 60,610, and in Great Britain October 9, 1924.

This invention relates to monogrammic advertising apparatus in which letters, figures, or designs are caused to form desired words, sentences, or designs which travel over a defined space, and it has for its object to make such apparatus more attractive, more easy to manipulate and generally more convenient to use. A further object is to reduce the cost of running such apparatus. I attain these objects by the mechanism illustrated in the accompanying drawing in which:—

Figure 1 is a view in front elevation and Figure 2 a view in side elevation of a complete apparatus.

Figure 3 is a view in plan and Figure 4 a view in elevation showing the mechanism of an apparatus particularly adapted for repetition work. Figures 5 and 6 are broken views in plan and elevation respectively—on an enlarged scale—of the button collecting elements. Figures 7 and 8 are views in front and side elevation respectively—also on an enlarged scale—of one of the buttons. Figure 9 is a view in section on line 9 Figure 4, and Figure 10 is a broken view in section on line 10 Figure 4.

Similar parts are denoted by like numerals of reference throughout the several views.

In bearings carried by a suitably shaped frame 0 are two rollers 1 and 1 which are located at such a distance apart as will provide for the simultaneous exposure of the necessary or desired number of words, one of said rollers being driven through suitable reducing gear by an electric motor 2. These rollers are provided with a number of circumferential grooves 3 which adapt said rollers to receive a plurality of endless belts 4. Any suitable means such as springs 5 may be employed to press the bearings of one of the rollers 1 away from the bearings of the other of said rollers for the purpose of keeping the belts 4 taut.

Each of the belts 4 carries a plurality of buttons 6 which are so mounted that they are capable of longitudinal adjustment relative both to the belt and to one another. A convenient method of mounting said buttons on said belts is to provide them with eyes 7 on their backs by which they can be threaded on to the belt and kept in frictional engagement with same.

The buttons 6 are grouped on their belts 4 to form the desired letters by means of a

series of controlling fingers 8 which are formed on or fixed to vibrating arms or armatures 8* which are actuated by electro-magnets 9. These fingers have hook-shaped ends and operate to gather the buttons on the under sides of the belts and to release them at the desired intervals to form the desired letters, figures or designs. The fingers 8 are mounted in a frame 26 so that they register with the belts 4. Said fingers—which as shown in Figure 5 are of L section—have hooks 27 on their ends which are adapted to engage with the eyes of the buttons 6. These fingers are individually controlled by separate electro-magnets 9 which are carried by the frame 26 and are caused to function at the necessary time to operate the fingers 8 to release the buttons by means of a "make and break" system operated by means of a travelling perforated tape 12 after the manner of the cards employed in a Jacquard loom.

A convenient embodiment of this device comprises an insulated element 10 which may conveniently take the form of a roller over which the perforated tape 12 passes and with which a series of brushes 15 contact through the perforations in said tape forming the letters, figures or designs of the matter to be displayed said insulated element and said brushes being in circuit with the electro-magnets 9 and any suitable source of electric energy.

The tape 12 after passing over the roller 10 passes over a drum 13 which is driven by a frictionally contacting roller 14 the shaft 28 of which is driven by the motor 2 through reduction gearing 29 and 30, the axle of the adjacent roller 1 and a lay shaft 3' coupled to said axle and to the shaft 28 by bevel gearing. The roller 10 is driven from the shaft 28 by chain gearing 42.

It will be understood that any desired number of belts 4 may be employed according to the size that is the depth of the letter to be displayed and that there is co-operating with each of said belts a collecting and distributing finger 8, and electro-magnet 9, and a brush 15. In order to keep the brushes 15, which consists of relatively thin spring wires, in their proper positions relative to the tape 12 they are each guided and supported by a fork 17 carried by the support 16, on which the brushes are mounted.

When the apparatus is intended to be em-

ployed for displaying matter such as news which necessitates a rapid change of tapes said tapes may simply hang freely over the element 10 and the roller 13, but if the apparatus is intended for use in shop windows or the like for repetition display the tape 12 is creased so as to lie in permanent folds which can be contained in a container 18 within the frame 0 so as to occupy a minimum of space as shown in Figures 3 and 4. The front of this container may conveniently be glazed as indicated in Figure 4 of the accompanying drawings in order that the folding of the tape can be observed. In this construction one end of the tape passes out of the container 18 through an aperture 19, passes over the element 10 and the roller 13, and thence to a folding device which comprises a chute 20 which depends into the container 18 at the end opposite to the outlet 19 and terminates in a flared and approximately horizontally disposed outlet 31. Adjacent to this outlet are two shafts 32 and 33 mounted to rotate in brackets 34 and 35 located at the top and bottom respectively of the container 18 and above and below said outlet 31 are shafts 36 and 37 mounted to rotate in brackets 38 and 39. The shafts 32, 33, 36 and 37 carry chain wheels those on the shafts 32 and 36 being geared together by a chain 21 and those on the shafts 33 and 37 by a chain 22. These chains function to gather the tape 12 after it passes out of the chute 20 and causes it to fall into its permanent folds. The shaft 37 may conveniently be driven from the shaft 28 by belt gearing 40 and the shaft 36 from the shaft 37 by a cross belt gearing 41.

To ensure a definite contact between the tape 12 and the element 10 tension may be put on said tape as it passes over said element which may conveniently be done by means of a spring finger 23 which presses said tape into contact with a fixed plate 24 as shown in Figure 4. The buttons consist of cups having flat bottoms and relatively vertical sides and of fillings of glass or other substance which are preferably faceted so as to increase the brilliancy of their faces. To increase the visibility of the buttons and therefore of the signs as a whole a reflected light may be thrown on to the face of the apparatus by means of a series of angularly arranged electric lamps 25 as shown in Figure 2.

In operation the letters or the like are formed on the bands 4 by the action of the fingers 8 grouping the buttons 6 on said bands under the action of the electro-magnets 9 which are caused to function at the necessary time to effect the desired grouping of the buttons by the "make and break" device controlled by the perforated tape.

What I claim is:—

1. A monogrammic advertising apparatus

comprising a plurality of endless travelling belts, means for driving said belts, a plurality of buttons frictionally mounted on said belts, a plurality of fingers adapted to collect said buttons and to distribute them on the belts, electromagnets operating said fingers, a source of supply of electric current in circuit with said electro-magnets, a tape having the letters, figures, or designs forming the matter to be displayed in the form of a series of perforations, an insulated element in circuit with said electromagnets over which said tape passes, a plurality of brushes in circuit with the electro-magnets which contact the insulated element through the perforations in said tape, and means for causing said tape to travel past said contact making brushes.

2. A monogrammic advertising apparatus comprising a plurality of endless travelling belts located side by side, means for driving said belts so that they travel at a uniform speed, a plurality of buttons frictionally mounted on each of said belts so that their positions on same can be varied, a plurality of fingers adapted to collect said buttons and to distribute them on the belts, electro-magnets controlling said fingers, a source of supply of electric current in circuit with said electro-magnets, a tape having the letters, figures, or designs forming the matter to be displayed in the form of a series of perforations, an insulated electrically conductive element over which said tape passes which is in circuit with said electro-magnets, a plurality of brushes each of which is in circuit with one of the electro-magnets said brushes being adapted to contact said insulated conductive element through the perforations in said tape and thus cause the electro-magnets to actuate the collecting and distributing fingers, and means for traversing said tape past said contact making brushes.

3. A monogrammic advertising apparatus comprising a plurality of endless travelling belts located side by side, means for driving said belts so that they travel at a common uniform speed, a plurality of buttons frictionally mounted on each of said belts so that their positions on same can be varied, a plurality of fingers adapted to collect said buttons and to distribute them on the belts, electro-magnets controlling said fingers, an accumulator in circuit with said electro-magnets, a tape having the letters, figures, or designs forming the matter to be displayed in the form of a series of perforations, an insulated drum over which said tape passes which is in circuit with said electro-magnets, a plurality of brushes which are in circuit with the electro-magnets and which contact said insulated drum through the perforations in said tape and thus cause the electro-magnets to actuate the collecting and distributing fingers, a secondary drum over

which the tape passes, and means for frictionally driving said secondary drum.

4. A monogrammic advertising apparatus comprising a plurality of endless travelling belts located side by side, means for driving said belts so that they travel at a common uniform speed, a plurality of buttons frictionally mounted on each of said belts so that their positions on same can be varied, a plurality of fingers adapted to collect said buttons and to distribute them on the belts, electro-magnets controlling said fingers, a source of supply of electric current in circuit with said electro-magnets, a tape having the letters, figures, or designs forming the matter to be displayed in the form of a series of perforations, an insulated element over which said tape passes which is in circuit with said electro-magnets, a drum over which said tape passes and by which it is caused to rotate, means for driving said drum, and a plurality of brushes each of which is in circuit with one of the electro-magnets said brushes being adapted to contact said insulated element through the perforations in said tape and thus cause the electro-magnets to actuate the collecting and distributing fingers.

5. An advertising apparatus comprising a plurality of endless travelling belts located side by side, means for driving said belts so that they travel at a common uniform speed, a plurality of buttons frictionally mounted on each of said belts so that their positions on same can be varied, a plurality of fingers adapted to collect said buttons and to distribute them on the belts, electro-magnets controlling said fingers, a source of electric current in circuit with said electro-magnets, an endless tape carrying the letters, figures or the like forming the matter to be displayed in the form of a series of perforations, an insulated electrically conductive element over which said tape passes which is in circuit with the electro-magnets, a plurality of brushes each of which is in circuit with one of the electro-magnets said brushes being adapted to contact said insulated conductive element through the perforations in said tape, means for folding said tape after it has passed said brushes and means for causing said tape to travel past said brushes.

6. An advertising apparatus comprising a plurality of endless travelling belts located side by side, means for driving said belts so that they travel at a common uniform speed, a plurality of buttons frictionally mounted on each of said belts so that their positions on same can be varied, a plurality of fingers adapted to collect said buttons and to distribute them on the belts, electro-magnets controlling said fingers, an accumulator in circuit with said electromagnets, an endless tape carrying the letters, figures or the like forming the matter to be displayed in the

form of a series of perforations, an insulated metallic roller over which said tape passes and which is in circuit with the electro-magnets, a secondary roller over which said tape passes and by which it is caused to travel, means for driving said secondary roller, a plurality of brushes each of which is in circuit with one of the electro-magnets said brushes being adapted to contact said insulated roller through the perforations in said tape, and means for folding said tape after it has passed said brushes.

7. An advertising apparatus comprising a plurality of endless travelling belts located side by side, means for driving said belts so that they travel at a common uniform speed, a plurality of buttons frictionally mounted on each of said belts so that their positions on same can be varied, a plurality of fingers adapted to collect said buttons and to distribute them on the belts, electro-magnets controlling said fingers, an accumulator in circuit with said electro-magnets, an endless tape carrying the letters, figures or the like forming the matter to be displayed in the form of a series of perforations, an insulated electrically conductive element over which said tape passes and which is in circuit with the electro-magnets, a drum over which said tape passes and by which it is caused to travel, means for driving said drum, a plurality of brushes each of which is in circuit with one of the electro-magnets said brushes being adapted to contact said insulated conductive element through the perforations in said tape, means for folding said tape after it has passed said brushes and means for creating a tension on said tape as it travels past said brushes.

8. An advertising apparatus comprising a plurality of endless travelling belts located side by side, means for driving said belts so that they travel at a uniform speed, a plurality of buttons having eyes by which they are threaded on said belts and kept in frictional engagement with them, a plurality of fingers adapted to collect said buttons and to distribute them on the belts, electro-magnets for controlling said fingers in circuit with a source of electric current, a tape carrying the letters, figures or the like forming the matter to be displayed in the form of a series of perforations, an insulated electrically conductive element over which said tape passes which is in circuit with the electro-magnets, a plurality of contact making brushes each of which is in circuit with one of the electro-magnets said brushes being adapted to contact said insulated conductive element through the perforations in said tape and means for causing said tape to travel past said contact making brushes.

9. An advertising apparatus comprising a plurality of endless travelling belts located side by side, means for driving said belts so

that they travel at a uniform speed, a plurality of buttons having eyes by which they are threaded on said belts and kept in frictional engagement with them, a plurality of fingers adapted to collect said buttons and to distribute them on the belts, electro-magnets for controlling said fingers in circuit with a source of electric current, a tape carrying the letters, figures or designs forming the matter to be displayed in the form of a series of perforations, an insulated electrically conductive element over which said tape passes which is in circuit with the electro-magnets, a plurality of contact making brushes in circuit with the electro-magnets said brushes being adapted to contact said insulated conductive element through the perforations in said tape distributing fingers, means for imparting motion to said tape and means for putting a tension on said tape as it passes over said insulated conductive element.

10. A monogrammic advertising appa-

ratus comprising a plurality of endless travelling belts located side by side means for driving said belts so that they travel at a uniform speed, a plurality of buttons frictionally mounted on said belts, a plurality of elements adapted to control the positions of said buttons on said belts, electro-magnets for actuating said controlling elements in circuit with a source of electric current, a tape having perforations forming the letters, figures or designs forming the matter to be displayed, an insulated electrically conductive element over which said tape passes which is in circuit with the electro-magnets a plurality of brushes each of which is in circuit with one of the electro-magnets said brushes which contact said insulated electrically conductive element through the perforations in said tape and means for causing said tape to travel between said brushes and the insulated conductive element.
